J. L. Rowley,

Washing Machine

No 23,268.

Patented Mar 15, 1859.

Fig. 2

Fig. 1

UNITED STATES PATENT OFFICE.

JAMES L. ROWLEY, OF ANGOLA, INDIANA.

WASHING-MACHINE.

Specification of Letters Patent No. 23,268, dated March 15, 1859.

To all whom it may concern:

Be it known that I, JAMES L. ROWLEY, of Angola, in the county of Steuben and State of Indiana, have invented a new and Improved Mode of Constructing Washing-Machines; and I do hereby declare that the following is a full and exact description thereof, reference being had to the annexed drawings and to the letters of reference marked thereon.

The nature of my invention relates to the peculiar manner of forming the bottom of the box with ribs and pins or knuckle joints and also in the formation of the rubber and its adjustability to the clothes, and in the manner of working the same, as attached to a vibratory shaft to which the working handles are attached; as hereinafter more fully set forth in which—

Figure 1, is a plan of the sides, ends, and bottom, of the machine, and Fig. 2, represents a cross section at the red line on Fig. 1.

The same letters on each figure refer to the same parts.

A, A, the sides and ends of the machine, B, B, & C, the bottom D, D, the diagonal ribs or rubbers E, E, the knuckles or rubbing pins.

F, is the vibrating rubber, suspended to the shaft G, and is worked by the handles H, H, which are connected with the shaft G by the rods I, I. By this mode of operation the clothes have a more direct tendency to friction with the bars or ribs D, than when the action is on a direct or parallel line, the pins E, Fig. 1, being set alternately with the spaces, between the ribs D and the pins E, in the rubber F, being set alternately with the pins in the bottom C, gives a threefold

action on the washing surface, which is a relief and saving in the time of washing, the rubber journals working in the slants J, J,

cut in the ends of the box give an opportunity of adjusting the rubber to the clothes be they few or many put into the box at a time 45 and the rubber is very readily, removed from the box by tipping the rubber over against the side of the box, which is performed by lifting the journals out of the slants and slipping, the whole to either side of the box 50 where it may rest until wanted, again, when it is replaced again to its working position by tipping it back and slipping it to the center of the tub when the journals will readily enter the slant and be ready for 55 action.

The great advantages derived from this mode of construction are that it is very simple in construction and easily kept in repair, and in heavy washing the labor of two 60 persons is very readily applied to it if desired.

Having thus fully described my improved washing machine, what I claim as new and desire to secure by Letters Patent is—

I claim constructing the bottom of the box with three sides of an octagon, the two outer sides to have ribs of an octagonal shape set at an angle of 45° with the sides of the box and the bottom to be horizontal with two rows of rubbing pins or knuckles set alternately with the valleys between the ribs D, D, in combination with the vibrating rubber, having the rubbing surface octagonal and the rubbing knuckles set so as to work alternately with the spaces between the pins in the bottom of the box and diagonally with the ribs on outer sides of the bottom B, B, in the manner and for the purposes set forth.

J. L. ROWLEY.
